GUN FIRING MECHANISM WITH ECCENTRIC SAFETY

C Walton Musser, Philadelphia, Pa.

Application June 9, 1952, Serial No. 292,602

15 Claims. (Cl. 89—23)

(Granted under Title 35, U. S. Code (1952), sec. 266)

The invention described herein may be manufactured and used by or for the Government for governmental purposes without the payment to me of any royalty thereon.

My invention relates broadly to gun firing mechanisms, and although not limited solely thereto, has particular reference to firing mechanisms used in test guns employed for the purpose of obtaining ballistic data on guns, powder, cartridge components and projectiles. For example, such guns could be advantageously used: (a) to test factors causing gun bore erosion and means for overcoming same; (b) for the accelerated testing of the corrosive properties of various propellant powders on gun components; and (c) for similar testing of the resistance of gun components to those corrosive powders and to erosion caused by a projectile moving rapidly through the gun barrel, as well as many other factors involved in determining the optimum design of firearms and ammunition.

Because of the variety of different purposes for which test guns are used, it is desirable that the firing mechanism for such guns be simply designed and constructed, durable and, of course, safe. For some purposes, it is additionally desirable that means be provided for easily and quickly increasing or decreasing the force applied to the mechanism's firing pin, and for having the movement of the mechanism's hammer control the action of electrical instrumentation associated with the gun.

Before my invention, firing mechanisms for erosion testing guns were built along the lines of firing apparatus used on conventional guns. These prior art firing devices were rather complicated in design, relatively fragile, lacked adequate striking force in many instances due primarily to insufficient extent of movement of the mechanism's hammer, and, for these and other reasons, were found unsuited for use on test guns. I have overcome these disadvantages and have introduced concepts new to the art by providing the firing mechanism hereinafter set forth.

To describe my invention briefly, it is constructed upon a breech member which is attached to the rear end of the gun's barrel and comprises, in essence, a crankshaft upon whose crankpin a hammer capable of an exceptionally large angular movement is rotatably mounted. The crankshaft, in turn, is mounted upon the breech member and, by means of a trigger lever attached thereto, is rotatable into one of two positions. Rotation of the crankshaft displaces the shaft's crankpin in relation to the face of the breech member so that, when the crankshaft is in one position, the hammer is automatically released from rotation-restraining means associated with the firing mechanism, and a preloaded torque spring having considerable rotative force compels the hammer to swing rapidly around the crankshaft and to impinge upon a firing pin which, in usual manner, detonates the ammunition contained in the gun. Additionally, the hammer, by its movement with the crankshaft in this position, completes an electric circuit which controls the action of electrical instrumentation associated with the gun for ballistics recording purposes.

When the crankshaft is in the other position, the ham-

2

mer, if accidentally released, moves rapidly around the crankshaft toward the firing pin with less rotative force, but, because of both the position of the crankpin relative to the face of the breech member and the shape of the hammer, the movement of the hammer is abruptly stopped before the hammer strikes the firing pin and before it completes the electric circuit which controls the action of the instrumentation. In this manner accidental detonation of the ammunition is avoided.

10 A broad object of my invention is to provide a durable, simply designed and constructed firing mechanism for use on guns of the character mentioned.

Another object is to provide a firing mechanism in which accidental discharge of the gun's ammunition is prevented.

Yet another object is to provide a firing mechanism in which the hammer is capable of an especially large extent of movement prior to firing the ammunition.

20 A further object is to provide a firing mechanism which is quickly and easily applicable to any one of numerous types and sizes of test guns.

A still further object is to provide a firing mechanism in which the force applied to the mechanism's firing pin can be quickly and easily increased or decreased.

25 Still another object is to provide a firing mechanism whose action controls the operation of electrical instrumentation associated with the gun.

The foregoing and other objects and advantages of my invention will become apparent from an inspection of the following description and the accompanying drawings wherein:

30 Fig. 1 is an end view of my firing mechanism showing the hammer in its "retracted" (i. e. awaiting firing) position. For convenience, this figure has been partly broken away and partly sectioned to expose some components which otherwise would not be visible.

35 Fig. 2 is a side view of the firing mechanism taken along line 2—2 of Fig. 1 showing how the hammer is held in the retracted position. For convenience of drawing, part of the gun's barrel and the anterior portion of the ammunition round used in the gun have been added.

40 Fig. 3 is a vertical cross-section taken along line 3—3 of Fig. 1 showing some structural details of the mechanism. The part shown in broken line represents a portion of the 45 firing mechanism's trigger lever which has been superimposed to show its position relative to the parts shown in solid line.

45 Fig. 3A is a vertical cross-section similar to Fig. 3, but showing some parts after having been moved to a different position. Again, a portion of the firing mechanism's trigger lever has been superimposed in broken line to show its position relative to other parts.

50 Fig. 4 is a vertical cross-section taken along line 4—4 of Fig. 1. In addition to showing more structural details of my invention, this figure shows how the firing mechanism's hammer, having been accidentally released from the Fig. 55 2 retracted position, is prevented from striking the mechanism's firing pin. Note the position of the trigger lever, a portion of which has been superimposed in broken line.

55 Fig. 4A is a view similar to Fig. 2 but showing how movement of the trigger lever to the position previously indicated in Fig. 3A disengages the hammer from the sear. In Fig. 4A the hammer is fully disengaged from the sear, and is just about to move to the position shown in Fig. 4B.

60 Fig. 4B is a view similar to Fig. 4A, but partly sectioned, and showing how the firing mechanism's hammer impinges upon the mechanism's firing pin during normal operation of the mechanism. Note the position of the trigger lever, a portion of which has been superimposed in broken line, relative to the position shown in Fig. 4.

65 Fig. 5 is an oblique cross-section taken along line 5—5

of Fig. 4B and showing more structural details of my firing mechanism.

For convenience of description my invention may be considered as comprising the breech assembly 10 (see Figs. 1, 2, 4 and 4B), and the crankshaft assembly 11 (see Figs. 1 to 5). The essential details of these assemblies follow.

Breech assembly

The basic structural component of this assembly is the cylindrical, cup-like breech member 12 (see Figs. 1, 2 and 4) having a rear end 13 (see Figs. 1 to 5) and a forward end 14 (see Figs. 2, 4 and 4A). As shown in Fig. 4, the forward end is internally threaded, and is attached to the rear end 15 of the gun's barrel 16.

Axially slidable toward and away from the barrel's rear end, in the accommodating, stepped opening 17 in the central portion of the breech member, is a firing pin having a shank 18 (see Figs. 1, 2 and 4) and a somewhat larger diametered body 19 (see Fig. 4). As shown in the latter figure, the firing pin's shank extends beyond the rear face 20 of breech member 12 when the firing pin is at the limit of its available movement away from the barrel's rear end.

Secured inside the breech member, as by screws 21 (one of which is shown in Fig. 4), is a wear plate 22 having a central opening 23 into which projects a tip 24 of the firing pin. This wear plate, by virtue of the size of central opening 23, serves to limit the firing pin's forward movement, during operation of my invention, and also to provide a durable surface against which can abut the base end 25 of an ammunition round 26 accommodated in the gun's bore.

When the firing pin is at its rearwardmost position (see Fig. 4), the pin's tip 24 is substantially flush with the forward surface 27 of the wear plate, and, when the firing pin is at its forwardmost position (not shown), the pin's tip projects somewhat beyond the wear plate's forward surface in order to detonate a percussion primer 28 which forms part of ammunition round 26.

Secured to the breech member's rearmost face 20, but electrically insulated therefrom, as by an enameled coating or other convenient means (not shown), is a contact spring 30 (see Figs. 1, 2, 4 and 4B) which is fastened in place by screws 31. As seen in Figs. 2 and 4, the inner end 32 of this spring (i. e. toward the center of breech member 12) is somewhat removed from the breech member's face 20; and the outer end 33 of the spring (i. e. away from the breech member's center) contains an electrical socket 34 which is secured in place by means of a locknut 35. This socket is electrically connected to contact spring 30. As shown in Fig. 4, nut 35 and socket 34 extend into, but do not touch, the accommodating recess 36 formed in the breech. More information concerning contact spring 30 and electrical socket 34 will be given later in discussing the operation of my invention.

Located at the breech member's forward end 14 on a radial line extending from the axis of breech is a blind groove 40 (see Fig. 4). Accommodated in this groove for pivotal movement toward and away from the breech member's rearmost face 20 is a sear 41 having a hooked, outer end 42 (see Figs. 2, 4 and 4A). This sear is attached to the breech member by means of a shoulder screw 43 (see Fig. 4) whose body 44 passes through an opening in the sear, and whose smaller diametered shank 45 threads into the breech member. As shown in Fig. 4, sear 41 is constantly urged toward the breech member's rearmost face by means of a coil spring 46 (see Fig. 4), one end of which bears against the sear, and the other end of which bears against the head 47 of the shoulder screw.

Additionally, breech member 12 is provided with a radially extending arm 48 (see Figs. 1, 2 and 4B) which, during operation of my invention, aids in threading and unthreading the breech member from barrel 16, and with

the radially extending vent hole 49 (see Fig. 4) which extends between the outside of the breech member and its central, stepped recess 17.

Crankshaft assembly

Crankshaft assembly 11 comprises, principally, a crankshaft 50 (see Figs. 1 to 5), a hammer 51 (see Figs. 1, 2, 4 and 5), a torque spring 52 (see Figs. 1 and 5), and a trigger lever 53 (see Figs. 1 to 5). In a manner to be described later, crankshaft assembly 11 is joined to a crankshaft bracket 54 (see Figs. 1 to 5) which, in turn, is secured to breech member 12.

Crankshaft 50 comprises a journal portion 55 (see Figs. 1 and 5), and an elongated crankpin portion 56 (see Figs. 1 to 5).

Hammer 51 is a bar-like member having the rearward and forward surfaces 57 and 58, respectively (see Figs. 2, 4, 4A and 4B), which are conveniently shaped for optimum functioning. This hammer is rotatably mounted upon crankpin 56 which passes through one end of the hammer and which is so positioned in the assembly that the hammer is capable of approximately two hundred and seventy degrees (270°) rotation about the crankpin's axis (see Figs. 4, 4B and 5).

Torque spring 52, left-hand wound, is located on crankpin 56 between journal portion 55 and the adjacent side of hammer 51. As shown in Figs. 1 and 5, the left end 59 of this spring is anchored in a recess (more than one of which may be provided) in the crankshaft's journal portion 55, and, as shown in Fig. 5, the right end 60 of the torque spring is anchored in a similar recess (more than one of which may also be provided) formed in the side of the hammer.

Prior to later joining of crankshaft assembly 11 to crankshaft bracket 54, torque spring 52 may be wound up so as constantly to urge hammer 51 to rotate upon crankpin 56 in a counterclockwise direction (as viewed in Figs. 2, 4, 4A and 4B) with the desired energy.

Adjacent the side of hammer 51 opposite torque spring 52 is a trigger lever 53 (see Figs. 1 to 5). Projecting from the inner surface (i. e. toward hammer 51), at one end of the trigger lever is a bearing lug 61 (see Figs. 3, 3A and 5). This lug is provided with an L-shaped groove 62, semi-circular in cross section (see Fig. 5), and having bottom portions 63—64 which are substantially perpendicular to each other (see Figs. 3 and 3A).

Mounted on the trigger lever's bearing lug 61, and having limited rotation relative thereto, is a plate 65 which, in final assembly, is joined to the crankshaft bracket's right end 66 (see Figs. 1 to 3A, 4A and 5). Passing through this plate are screws 67 and 68 (see Figs. 1, 3 and 3A) which are used to secure plate 65 and the right end of crankshaft bracket 54 to breech member 12. In Figs. 3 and 3A it can be seen that screw 67, in passing through the plate, also passes through L-shaped groove 62, and thereby both limits the amount of relative rotation between trigger lever 53 and plate 65, and also prevents the trigger lever from being removed, axially, from that plate.

As best shown in Fig. 5, trigger lever 53 is secured in any convenient manner, as by a pin 69, to the end of crankpin 56 opposite journal portion 55. Notice in that figure, and also in Figs. 3 and 3A, that the axis of the crankpin is eccentric to the axis of the trigger lever's bearing lug 61. Actually, the amount of displacement between these axes is the same as that existing at the crankshaft's opposite end between the crankpin and journal portion 55. As is usual practice, before trigger lever 53 is pinned to crankpin 56, the axes of journal portion 55 and bearing lug 61 are positioned concentric to each other.

Crankshaft bracket 54 consists of a base portion 75 (see Figs. 1, 4, 4B and 5) at the left end of which (see Fig. 1) is the upright 77 (also see Figs. 4, 4B and 5). At its right end 66, earlier mentioned (see Figs.

1 to 3A, 4A and 5), the base portion is somewhat reduced in thickness for serving as a bed upon which the crankshaft assembly's plate 65 is attached for rotatably supporting that assembly's right end. Between the left and right ends, base 75 has the beveled sides 78 and 79 (see Figs. 1, 4 and 4B) which are so inclined for functional reasons.

Projecting to the left from the side of upright 77 is an arm 80 (see Figs. 1 and 5). Passing through the upright and extending axially part way into this arm is a blind, spring recess 81 (see Figs. 1, 4, 4B and 5) in the bottom of which is a journal recess 82 (see Figs. 1 and 5). As apparent in Figs. 1 and 5, spring recess 81 and journal recess 82 are eccentric to each other by an amount which permits proper movement of crankpin 56.

Secured in any convenient manner (not shown) to the outer end 83 of arm 80 (see Figs. 1 and 5) is a handle 84 (see Figs. 1, 2, 4, 4B and 5). This handle is so positioned on arm 80 that, when the crankshaft bracket is attached to breech member 12, the axis of the handle parallels the breech member's axis, and is substantially the same radial distance from that axis as the center of the spherical knob attached to the breech member's radially extending arm 48 (see Fig. 1). Thus, by aid of arm 80 and handle 84, the threading and unthreading of breech member 12 from the gun's barrel is further facilitated.

Crankshaft bracket 54 is mounted upon the beveled seat 90 formed in breech member 12 (see Figs. 2 to 5), and is secured thereto, at its left end, by means of screws 91 (see Fig. 1). At its right end, the crankshaft bracket is secured by means of the earlier-mentioned screws 67 and 68 in a manner later to be described. When mounted upon the breech member, the bracket's base portion 75 is substantially diametrically opposed the breech member's contact spring 30 (see Fig. 1), and the base portion's beveled side 78 is substantially coplanar with the breech member's outer surface 20 (see Figs. 4 and 4B).

After crankshaft bracket 54 is attached to breech member 12 by means of screws 91 (see Fig. 1), crankshaft assembly 11 is then added to the crankshaft bracket. This is done as follows: The crankshaft's journal portion 55 is inserted into journal recess 82 in the bracket's arm. At the same time, torque spring 52 is accommodated in the arm's spring recess 81. That done, hammer 51 is then adjacent upright 77 (see Figs. 1 and 5).

Plate 65 is then positioned upon right end 66 of the bracket's base portion, and screws 67 and 68 (see Figs. 3 and 3A) are passed through the bracket's base portion 66 and are threaded into the breech member. However, before adding crankshaft assembly 11 to crankshaft bracket 54, torque spring 52 may be wound up in well-known manner so as forcefully to urge hammer 51 to rotate in a counterclockwise direction (as viewed in Figs. 1, 4, 4A and 4B) upon crankpin 56 with the desired force.

When plate 65 is secured to the crankshaft bracket's base portion 66, the trigger lever's bearing lug 61 becomes concentric with the arm's journal recess 82. Therefore, rotation of crankshaft 50 will be about the axis common to those parts, and will cause the axis of crankpin 56 to be moved in usual, well-known manner. Now with crankshaft assembly 11 joined to crankshaft bracket 54, co-joined crankshaft 50 and trigger lever 53 are rotatable to one of two positions: a "safe" position shown in Figs. 1, 2, 3 and 4, or a "firing" position shown in Figs. 3A, 4A, 4B and 5; and hammer 51 is rotatable through a large angular extent upon crankpin 56 to any one of three positions: a "retracted" position shown in Figs. 1, 2, and 4A, a "non-firing, released" position shown in Fig. 4, or a "firing" position shown in Figs. 4B and 5.

The movement of trigger lever 53 and therefore crankshaft 50 to the "safe" position is limited by bottom portion 63 of L-shaped groove 62 in the trigger lever's bearing lug 61 (see Fig. 3). This portion, as shown in Fig. 3, abuts screw 67. The movement of the trigger lever, and therefore the crankshaft, to the firing position is limited

by the groove's other bottom portion 64 which abuts screw 67 when the trigger lever is moved to the firing position.

When crankshaft 50 and trigger lever 53 are in the "safe" position (see Figs. 2, 3 and 4), the perpendicular distance from the breech member's rearmost face 20 to the axis of crankpin 56 is less than the perpendicular distance from the hammer's forward surface 58 to the crankpin's axis. Therefore, the hammer's forward surface cannot strike the firing pin if the hammer is released (see Fig. 4).

However, when the crankshaft and the trigger lever are in the "firing" position (see Figs. 3A, 4A and 4B), the axis of the crankpin is so displaced, relative to outer face of the breech member, that the perpendicular distance from the breech member's rearmost face to the crankpin's axis is substantially equivalent to the perpendicular distance from the hammer's forward surface 58 to the axis of the crankpin plus the thickness of contact spring 30. As a consequence of this condition, hammer 51, when released, is able to impinge upon the firing pin (see Fig. 4B) thereby moving it against percussion primer 28 to discharge ammunition round 26 in well-known manner.

Hammer 51 is manually placed in the retracted position by rotating it in a clockwise direction as viewed in Figs. 4 and 4B. This movement of the hammer initially or further winds up torque spring 52, as the case may be, and moves the trigger lever, if in the firing position, back to the safe position. When fully retracted, the ledge 92 formed on the hammer's free end latches under the sear's hooked end 42 (see Fig. 2), and is thus held in position until released.

If the latching engagement between the hammer and the sear is accidentally released while crankshaft 50 and trigger lever 53 are in the safe position (see Fig. 4), the hammer, under the action of torque spring 52, moves rapidly toward the firing pin, but, because of the relation between the rearmost face of the breech member and the crankpin's axis, the hammer cannot travel far enough to strike the firing pin (also see Fig. 4). This is the "non-firing, released" position. Thus accidental firing of the gun is prevented.

Hammer 51 moves from the "retracted" to the "firing" position as a result of moving the trigger lever and the attached crankshaft to the firing position shown in Figs. 3A, 4A and 4B. During this movement, the axis of the crankpin is displaced in relation to the breech member's face so that the hammer is pulled free from latching engagement with the sear. Then, under action of the torque spring, the hammer moves rapidly in a counterclockwise direction about crankpin 56 and, because of the relationship between the outer or rear face of the breech member and the crankpin's axis, strikes the firing pin (see Fig. 4B).

Thus, although torque spring 52 constantly tends to move the hammer from the "retracted" position to the two last-named positions, whether or not the hammer assumes the "non-firing," released position or the "firing" position depends upon the position of the crankpin relative to the rearmost face of the breech member.

Also, it can be noticed that movement of trigger lever 53, by either manual or lanyard operation, from the "safe" position (Fig. 4) to the "firing" position (Fig. 4B), further preloads torque spring 52, thereby imparting additional potential energy thereto. This action increases the total energy deliverable by hammer 51 to the firing pin when the hammer is released from the sear's hooked end 42. In other words, the energy available to fire the primer is the combination of the energies introduced into the torque spring by the optional winding thereof at assembly, by moving hammer 51 to its "retracted" position and by moving trigger lever 53 to its "safe" position. This total energy is of greater magnitude when the hammer is released with the trigger lever in the firing position than when the trigger lever is in the safe position. The difference in magnitude is caused by the additional potential

nergy imparted to the torque spring in moving the trigger lever from the safe to the firing position.

Operation

Having presented the components of my invention and having described the essential features thereof, the invention's operation will now be described.

Ammunition round 26 is placed in the gun barrel's rear end 15 with the round's base end 25 extending somewhat beyond the barrel's rear end (see Fig. 4). With the aid of radially extending arm 48 and the bracket's arm 36, breech member 12 is threadedly attached to the rear end of the gun barrel until the breech member's wear plate 22 abuts the base end of ammunition round 26 with more or less pressure, as desired.

Hammer 51 is then moved to its retracted position where it is held by sear 41 (see Fig. 2). As earlier explained, moving the hammer to the retracted position also moves the trigger lever to the safe position. This is accomplished through the agency of the torque spring which, it is apparent, serves a two-fold purpose. Note at this point, that if the firing pin's tip 24 happened to be projecting beyond the surface of the wear plate, the firing pin would be moved toward the rearmost face 20 of the breech until shank 18 projects therefrom and until the firing pin's tip is substantially flush with the wear plate's forward surface 27.

After breech member 12 is attached to gun barrel 16, and hammer 51 retracted, electrical instrumentation 95 (see Fig. 4) to be controlled by the action of hammer 51 is connected to a convenient source of electricity by means of a connecting plug 96. Further, an electrical lead 97 is connected for electrical conduction to barrel 16 by the ground connections schematically indicated at 98 and 101, and another lead 99 is connected for electrical conduction to contact spring 30 by means of the lead's terminal 100 which is inserted in the contact spring's electrical socket 34 (see Fig. 4).

When it is desired to fire the gun, trigger lever 53 is moved from the "safe" position, shown in Figs. 1 to 3 and 4, to the "firing" position shown in Figs. 3A, 4A, 4B and 5.

Assuming hammer 51 to be held in its "retracted" position by sear 41 (see Fig. 2), as the trigger lever is moved from the "safe" position shown in Figs. 2, 3 and 4 toward the "firing" position shown in Figs. 3A, 4A and 4B, crankpin 56 is moved away from the sear (from right to left in Fig. 2), and the torque spring is given additional potential energy, as earlier explained. This movement of the crankpin pulls the end of the ledge 92 out of engagement with the resiliently mounted sear 41. When the trigger lever reaches the "firing" position (see Figs. 3A, 4A and 4B), the hammer has been moved away from the sear by the action of the crankshaft until the hammer is fully disengaged from the sear (see Fig. 4A). At that moment, torque spring 52 causes the hammer to rotate upon the crankpin from the position shown in Fig. 4A to that shown in Fig. 4B. In moving, the hammer strikes the firing pin and moves it against primer 28 of the ammunition round, thereby firing the gun.

At the time of striking the firing pin, the hammer also meets contact spring 30. This action completes an electrical circuit through instrumentation 95 used to indicate or record the results of the firing.

If, by mistake or accident, hammer 51 should be released from sear 41 while trigger lever 53 is in the "safe" position, or while the hammer is being moved to its "retracted" position, the hammer will promptly rotate about crankpin 56 toward the firing pin, but the hammer's movement will be abruptly terminated before it strikes the firing pin because the axis of the crankpin is not properly disposed relative to the rear face 20 of the breech member. As a result, the particular shape of the hammer's forward surface 58 prevents full movement of the hammer which comes to rest a safe distance from the

projecting firing pin. Thus, my firing mechanism cannot become operative to fire the gun unless trigger lever 53 and the attached crankshaft 50 are in proper firing position.

Moreover, since the trigger lever had not been moved to the "firing" position, and thus had not imparted additional potential energy to the torque spring, my mechanism has a dual safety feature. Not only will the hammer be prevented from striking the firing pin, as explained above, but in addition, the very energy possessed by the hammer upon its accidental release will be far less than it has when released after the trigger lever is in the "firing" position.

From the foregoing it will be apparent that I have provided a durable, simply designed and constructed firing mechanism; that I have provided a firing mechanism in which the accidental discharge of the gun's ammunition is prevented; that I have provided a firing mechanism in which the hammer is capable of an especially large extent of movement prior to firing the ammunition; that I have provided a firing mechanism which is quickly and easily applicable to any one of numerous types and sizes of test guns; that I have provided a firing mechanism in which the force applied to the mechanism's firing pin can be quickly and easily increased or decreased; and that I have provided a firing mechanism whose action controls the operation of electrical instrumentation associated with the gun.

Those skilled in the art will realize that my invention can be modified and varied in numerous ways without departing from its original spirit and scope. For that reason I do not wish to be limited in patent coverage to the narrow confines inherent in the illustrative embodiment of my invention here described, but, rather, only by the metes and bounds of the appended claims.

I claim:

1. A mechanism for firing percussion-detonatable ammunition carried by a gun including a breech member removably attachable to the gun's barrel, a firing pin slidably accommodated in said breech member for axial movement toward and away from the gun's barrel, a shaft rotatably supported on said breech member, a hammer rotatable on said shaft, a coiled torque spring around said shaft, one end of said spring being connected to said breech member and the other end of said spring being connected to said hammer so as constantly to urge that hammer toward said firing pin, restraining means on said breech member for releasable latching engagement with said hammer and for selectively holding said hammer away from said firing pin against the force of said torque spring, and a lever attached to said shaft so that shaft can be moved rotatively for the purpose of increasing the potential torque given said torque spring whereby, upon release of said restraining means, said hammer will be caused by said torque spring to rotate on said shaft to strike said firing pin and thereby detonate the ammunition carried by the gun's barrel.

2. In a mechanism for firing percussion-detonatable ammunition carried by a gun and for simultaneously energizing instrumentation connected to the gun, the combination of a breech member removably attachable to the gun's barrel, a firing pin slidably accommodated in said breech member for axial movement toward and away from the gun's barrel, a shaft rotatably supported on said breech member, an electric contact member carried by said breech member but electrically insulated therefrom, recording instrumentation electrically connected to said electrical contact member, a hammer rotatable on said shaft so as to strike said firing pin and simultaneously to meet said contact member, a torque spring connected to said hammer so as constantly to urge that hammer toward said firing pin and toward said electrical contact member, restraining means attached to said breech member for selectively holding said hammer away from said firing pin and away from said electrical contact mem-

ber against the force of said torque spring, and a lever attached to said shaft so that shaft can be moved rotatively for the purpose of increasing the potential torque given said torque spring, whereby, upon release of said restraining means, said hammer will be caused by said torque spring to rotate on said shaft to strike said firing pin and detonate the ammunition, and will also be caused simultaneously to abut said electrical contact member so as to complete an electrical circuit connected across said electrical contact and breech members and thereby energize said recording instrumentation.

3. In a mechanism for firing percussion-detonatable ammunition carried by a gun, the combination of a breech member removably attachable to the gun's barrel, a firing pin slidably accommodated in said breech member for axial movement toward and away from the gun's barrel, a crankshaft mounted on said breech member and selectively rotatable to first and second positions relative to said breech member, a trigger lever secured to the crankshaft for selectively rotating said crankshaft to said first and second positions, and a hammer on the crankpin of said crankshaft, said hammer being displaced relative to said breech member as said crankshaft is rotated so that said hammer is rotatable a sufficient amount on said crankshaft to strike said firing pin and thereby to detonate the ammunition when said crankshaft is in the first position, but so that said hammer is rotatable an insufficient amount and is prevented from striking said firing pin by said breech member when said crankshaft is in the second position.

4. A mechanism for firing percussion-detonatable ammunition carried by a gun, comprising a breech member removably attachable to the gun's barrel, a firing pin slidably accommodated in said breech member for axial movement toward and away from the gun's barrel, a crankshaft mounted on said breech member and selectively rotatable to first and second positions relative to said breech member, a trigger lever secured to the crankshaft for selectively rotating said crankshaft to said first and second positions, a hammer rotatable on the crankpin of said crankshaft so that said hammer is displaced relative to said breech member as said crankshaft is rotated, a torque spring connected to said hammer so as constantly to urge that hammer toward said firing pin, and restraining means attached to said breech member for releasable latching engagement with said hammer and for selectively holding said hammer away from said firing pin against the force of said torque spring, whereby when said crankshaft is in the first position said hammer, under influence of said torque spring and upon release of said restraining means will rotate on said crankshaft to strike said firing pin and thereby detonate the ammunition, but will rotate on said crankshaft to strike said breech member and thereby be prevented from striking said firing pin when said crankshaft is in the second position.

5. A mechanism for firing percussion-detonatable ammunition carried by a gun and for simultaneously energizing instrumentation connected to the gun, such mechanism comprising a breech member removably attachable to the gun's barrel, a firing pin slidably accommodated in said breech member for axial movement toward and away from the gun's barrel, a crankshaft mounted on said breech member and selectively rotatable to first and second positions relative to said breech member, a trigger lever for selectively rotating said crankshaft to said first and second positions, an electrical contact member carried by said breech member but electrically insulated therefrom, recording instrumentation electrically connected to said electrical contact member, a hammer rotatable on the crankpin of said crankshaft so that said hammer is displaced relative to said breech member and relative to said electrical contact as said crankshaft is rotated, a torque spring connected to said hammer so as constantly to urge that hammer toward said firing pin

10 and toward said electrical contact member, and restraining means attached to said breech member for selectively holding said hammer away from said firing pin and away from said electrical contact member against the force of said torque spring, whereby when said crankshaft is in the first position said hammer, under influence of said torque spring, and upon release of said restraining means, will rotate on said crankshaft to strike said firing pin and thereby detonate the ammunition, and also simultaneously abut said electrical contact member so as to complete an electrical circuit connected across said electrical contact and breech members and thereby energize said recording instrumentation, but will rotate on said crankshaft to strike said breech member and thereby be prevented from striking said firing pin and from abutting said electrical contact member when said crankshaft is in the second position.

6. The combination, in a gun for firing percussion-detonatable ammunition, of a breech member removably attachable to the gun's barrel, a firing pin slidably accommodated in said breech member for axial movement toward and away from the gun's barrel, a crankshaft mounted on said breech member and selectively rotatable to first and second positions relative to said breech member, a trigger lever for selectively rotating said crankshaft to said first and second positions, an electrical contact member on said breech member but electrically insulated therefrom, recording instrumentation electrically connected to said electrical contact member, a hammer 20 rotatable on the crankpin of said crankshaft, a torque spring on said crankshaft with one end of the spring connected to the crankshaft and with the other end connected to said hammer so as constantly to urge the hammer toward said firing pin and toward said electrical contact member, and a sear mounted on said breech member for holding said hammer away from said firing pin and away from said electrical contact member against the force of said torque spring, whereby when said crankshaft is in the first position the hammer will be released from said sear and will rotate on said crankshaft sufficiently to strike said firing pin and thereby detonate the ammunition, and also simultaneously to abut said electrical contact member so as to complete an electrical circuit connected across said electrical contact and said breech members and thereby energize said recording instrumentation, but said hammer will rotate on said crankshaft and strike said breech member and thereby be prevented from striking said firing pin and from abutting said electrical contact member if said hammer is accidentally released from said sear while said crankshaft is in the second position.

7. The mechanism of claim 3 plus stop means for limiting the rotation of the crankshaft to the first and second position.

8. The combination of claim 6 plus a replaceable wear plate in the breech member for abutting the head end of the ammunition.

9. In a firing mechanism for percussion-detonatable ammunition, the mechanism having a rotatable, eccentric shaft and a hammer rotatably mounted thereon, the combination of: a torque spring for moving the hammer to the firing position, restraining means for holding the hammer in the retracted position against the force of said torque spring, and a trigger lever for rotating the eccentric shaft for the purpose of imparting increased potential torque to said torque spring and for the purpose of simultaneously moving said hammer relative to said restraining means so as to release the hammer from that restraining means.

10. The combination of claim 9 in which the torque spring is on the rotatable, eccentric shaft.

11. The combination of claim 9 in which the restraining means is releasably engageable with the hammer for holding the hammer in the retracted position against the action of the torque spring.

12. The combination of claim 9 in which the trigger lever is attached to the rotatable, eccentric shaft.

13. In a firing mechanism for a gun using percussion-detonatable ammunition, the combination of a breech member removably attached to the gun's barrel; a firing pin slidably accommodated in said breech member and adapted to fire the ammunition; a crankshaft supported by said breech member and selectively rotatable relative to the breech member to two positions; a safe position and a firing position; a hammer on said crankshaft for acting on said firing pin, said hammer, when traveling from a cocked position to its firing position, being moved on a rectilinear path by said crankshaft; a torque spring on said crankshaft for moving said hammer from the firing position in an arcuate path toward said firing pin; a sear on said breech member for releasable engagement with said hammer to hold the hammer in the cocked position against the action of said torque spring; and a trigger lever on said crankshaft for moving that shaft to the firing position, so that the hammer carried on the shaft is moved substantially rectilinearly from engagement with said sear into the hammer's firing position, and potential energy simultaneously is imparted to said torque spring; whereupon said hammer then rotates about said crankshaft under influence of said torque spring and strikes said firing pin to cause the ammunition to be fired.

14. The combination of claim 13 plus stop means for limiting the rotatability of the crankshaft to its two positions.

15. The combination, in a mechanism for firing percussion-detonatable ammunition carried in a gun and for simultaneously energizing instrumentation connected to the gun, of: a breech member removably attachable to the gun's barrel; a firing pin slidably accommodated in said breech member for axial movement toward and away from the ammunition; a replaceable wear plate in said breech member for abutting the ammunition; a crankshaft mounted on said breech member and selectively rotatable to one of two positions relative to said breech member; a safe position and a firing position; stop means for limiting the rotatability of said crankshaft; a hammer rotatable through a large angular expanse on the crankpin of said crankshaft; an electrical

contact in said breech member, but electrically insulated therefrom, in position to be contacted by said hammer when the hammer moves to the firing position; a torque spring on said crankshaft for moving said hammer toward the firing position and toward said electrical contact and serving also to move said crankshaft from the firing position to the safe position whenever said hammer is moved out of the firing position, one end of said torque spring being anchored in the crankshaft and the other end of that spring being anchored in the hammer; a sear yieldably positioned on said breech member for releasable engagement with said hammer so as to hold that hammer in the cocked position against the force of said torque spring; a trigger lever on said crankshaft for rotating that shaft to its firing position, thereby imparting increased potential energy to said torque spring, and simultaneously moving said hammer and releasing that hammer from engagement with said sear; and electrical instrumentation connected across said electrical contact and the gun's barrel, and adapted to be activated when said hammer moves to its firing position; whereby, when said crankshaft is in the firing position, said hammer will be released from said sear and will rotate on said crankshaft sufficiently far and with adequate force to strike said firing pin and thereby detonate the ammunition, and will also simultaneously abut said electrical contact so as to complete an electrical circuit to activate said electrical instrumentation, but said hammer will rotate on said crankshaft to strike said breech member and thereby be prevented from striking said firing pin and from abutting said electrical contact if said hammer is accidentally released from said sear while said crankshaft is in the safe position.
